(57) **ABSTRACT**

A new and distinct plum tree variety, *Prunus salicina*, cv. 'Suplumforty' is characterized by ripening mid-season. The new variety is further characterized by dark skin and reddish flesh color.

1 Drawing Sheet

1

Latin name of the genus and species claimed: *Prunus salicina*.

Variety denomination: 'Suplumforty'.

BACKGROUND AND SUMMARY OF THE
INVENTION

This invention relates to the discovery and asexual propagation of a new and distinct variety of plum, *Prunus salicina* cv. 'Suplumforty'. The new variety was first hybridized in 2002 and selected in July 2004 by Terry Bacon as breeder number: 'PL453RB'. The new variety was first evaluated by Terry Bacon near Wasco, Calif. in Kern County. The variety 'Suplumforty' was originated by hybridization.

The new variety 'Suplumforty' is characterized by ripening mid-season and having dark skin and reddish flesh color.

The seed parent is 'Suplumtwentysix' (the subject of U.S. Plant Pat. No. 13,395), and the pollen parent is an unknown plum in the breeding population. The parent varieties were first crossed in March of 2002, with the date of planting of the progeny being January 2003, and the date of first flowering being March 2004. The new plum variety 'Suplumforty' was first asexually propagated by Terry Bacon near Wasco, Kern County, Calif. in January 2006, by grafting.

The new variety 'Suplumforty' is distinguished from its seed parent, 'Suplumtwentysix', in that the new variety ripens about nineteen days later than 'Suplumtwentysix'.

The new variety 'Suplumforty' has a similar harvest time as 'Suplumeleven' (U.S. Plant Pat. No. 4,902), but the skin is darker and the flesh is more red in color. The new variety 'Suplumforty' has a harvest time seven days after Black Amber (unpatented).

The new variety 'Suplumforty' has been shown to maintain its distinguishing characteristics through successive asexual propagations by, for example, budding and grafting.

BRIEF DESCRIPTION OF THE PHOTOGRAPH

The accompanying color photographic illustration shows typical specimens of the foliage and fruit of the present new

2

plum variety 'Suplumforty'. The illustration shows the upper and lower surface of the leaves, an exterior and sectional view of a fruit divided across its suture plane to show flesh color, pit cavity and the stone remaining in place. The photographic illustration was taken shortly after being picked (shipping ripe) and the colors are as nearly true as is reasonably possible in a color representation of this type.

DETAILED DESCRIPTION OF THE PREFERRED
EMBODIMENT

Throughout this specification, color names beginning with a small letter signify that the name of that color, as used in common speech is aptly descriptive. Color names beginning with a capital letter designate values based upon The R.H.S. Colour Chart published by The Royal Horticultural Society, London, England.

The descriptive matter which follows pertains to 4 year old 'Suplumforty' plants on Nemared (unpatented) rootstock, grown in the vicinity of Wasco, Kern County, Calif., during July 2009, and is believed to apply to plants of the variety grown under similar conditions of soil and climate elsewhere.

25 **TREE**

General: (Measurements taken on 4 year old tree unless otherwise noted.)

Size.—Medium. Normal for most plum varieties.

Reaches a height of approximately 3 meters including normal pruning.

Spread.—Normal for most plum varieties. Approximately 3 meters.

Vigor.—Moderately vigorous.

Growth.—Semi-upright.

Productivity.—Very productive. Fruit set is usually two or more times desired amount for marketable size fruit.

Form.—Vase formed.

Bearer.—Regular.

<i>Fertility.</i> —Unknown.	5	<i>Form.</i> —Elliptic.
<i>Canopy density.</i> —Medium-dense.		<i>Tip.</i> —Acuminate.
<i>Hardiness.</i> —Half-hardy in all fruit growing areas of California.		<i>Base.</i> —V-shaped.
<i>Disease resistance/susceptibility.</i> —No specific testing for relative plant disease resistance/susceptibility has been designed. Under close observation in Kern County, Calif., no particular plant/fruit disease resistance/susceptibility has been observed.	10	<i>Margin.</i> —Crenate.
Trunk: (Measurements at approximately 30 cm above soil line.)		<i>Venation.</i> —Pinately veined.
<i>Diameter.</i> —Approximately 21 cm, varies with soil type, fertility, climatic conditions and cultural practices.		<i>Vein color.</i> —About 139D on lower surface.
<i>Texture.</i> —Medium shaggy, increases with age of tree.	15	<i>Surface texture.</i> —Smooth.
<i>Trunk color.</i> —About Grey-green 198C to Grey-brown 201A; becomes darker with age.		<i>Leaf blade (ratio of length to width).</i> —Medium.
Branches: (Measurements at approximately 90 cm above soil line.)		<i>Shape in the cross section.</i> —Flat.
<i>Size.</i> —Diameter ranges from approximately 6 to 20 approximately 9 cm.	20	<i>Profile.</i> —Somewhat flat.
<i>Texture.</i> —Smooth on first year wood, increasing roughness with tree age.		<i>Leaf blade tip.</i> —Usually in the plane of the leaf.
<i>Color.</i> —Branches vary from about Grey-brown 199B to Brown 200B.	25	<i>Undulation of margin.</i> —Absent.
<i>Number of lenticels.</i> —Medium, when present, about 2-3/cm ² .		<i>Petiole:</i>
<i>Lenticels density.</i> —Approximately 2-4 per cm ² .		<i>Average length.</i> —Medium; approximately 18 mm.
<i>Lenticels color.</i> —About Grey-brown 199C.	30	<i>Average diameter.</i> —Approximately 2 mm.
<i>Lenticels size.</i> —Medium, about 2 mm.		<i>Color.</i> —About 147C.
<i>Lenticels length.</i> —Approximately 3 mm.		<i>Leaf glands:</i>
<i>Lenticels width.</i> —Approximately 1 mm.	35	<i>Form.</i> —Reniform, Very rare.
Flowering shoots: (Data taken in July at midpoint of previous season shoots.)		<i>Average number.</i> —Most leaves have none. Where they exist about two/leaf.
<i>Size.</i> —Average diameter approximately 6 mm.		<i>Position.</i> —On leaf base.
<i>Color.</i> —Topside: About Grey-brown 197B. Underside: About Grey-brown 197B.	40	<i>Average size.</i> —Small; approximately 0.5 mm.
<i>Internode length.</i> —Medium; approximately 25 mm. Midway on flowering shoot.		<i>Color.</i> —About 200D.
<i>Flowering shoot lenticels.</i> —Sparse. Color: About Grey-orange 164B. Diameter: Approximately 0.5 mm.		FLOWERS
<i>Flowering shoot leaf buds.</i> —Shape: Obovate. Width: Approximately 0.8 mm. Length: Approximately 1 mm. Color: About Grey-orange 166C.	45	<i>General:</i>
<i>Flowering shoot flower buds.</i> —Shape: Obovate-pointed, borne usually on short spurs, approximately 1-3 cm long. Width: Approximately 1.3 mm. Length: Approximately 2 mm. Color: About Grey-orange 166C. Number per Spur: Usually 20-30 on short spurs. Position: Free.	50	<i>Flower blooming period.</i> —First bloom: Approximately February 26. Full bloom: Approximately March 1.
<i>Density of buds.</i> —Dense.		<i>Duration of bloom.</i> —Medium; approximately 10 days.
<i>Flower bud distribution.</i> —Generally 20-30 on short spurs.	55	<i>Diameter of fully opened flower.</i> —Medium, approximately 25 mm.
<i>Ratio of wood (leaf) buds to flowering buds.</i> —1/20 on short spurs.		<i>Flower aroma.</i> —Slight aroma.
		<i>Shape.</i> —Rosaceous.
		<i>Peduncle:</i>
		<i>Length.</i> —Medium; approximately 10 mm.
		<i>Diameter.</i> —Medium; approximately 1 mm.
		<i>Color.</i> —About Yellow-green 144B.
		<i>Pubescence.</i> —Absent.
		<i>Petals:</i>
		<i>Number.</i> —5.
		<i>Arrangement.</i> —Free.
		<i>Length.</i> —Approximately 10 mm.
		<i>Diameter.</i> —Approximately 10 mm.
		<i>Shape.</i> —Circular.
		<i>Apex shape.</i> —Rounded.
		<i>Base shape.</i> —Narrows at point of attachment.
		<i>Color.</i> —About White 155D.
		<i>Surface texture.</i> —Smooth.
		<i>Margins.</i> —Slightly undulating.
		<i>Claw length.</i> —Medium, approximately 2.0 mm.
		<i>Margin waviness.</i> —Medium, smooth and slightly wavy.
		<i>Base angle.</i> —Narrow.
		<i>Division of upper margin.</i> —Entire.
		<i>Pubescence of inner surface.</i> —Absent.
		<i>Pubescence of outer surface.</i> —Absent.
		<i>Sepals:</i>
		<i>Number.</i> —5.
		<i>Length.</i> —Approximately 3 mm.
		<i>Diameter.</i> —Approximately 2 mm.
		<i>Shape.</i> —Elliptic.
		<i>Color.</i> —About Yellow-green 144A.
		<i>Surface texture.</i> —Smooth.
		<i>Margins.</i> —Entire.
		<i>Positioning.</i> —Adpressed or touching petals.
		<i>FOLIAGE</i>
		<i>Leaves:</i>
		<i>Size.</i> —Medium.
	60	<i>Average length.</i> —Medium; approximately 81 mm without petiole.
		<i>Average width.</i> —Medium; approximately 36 mm.
		<i>Thickness.</i> —Medium, about 0.3 mm.
		<i>Color.</i> —Upper surface: About 147A. Lower surface: About 147B.

<i>Pubescence of inner surface.</i> —Absent.	5	<i>Ground color.</i> —About 144A, when visible.
<i>Pubescence of outer surface.</i> —Absent.		<i>Overcolor.</i> —About 187A.
Stamens:		<i>Taste.</i> —Mildly tart.
<i>Number.</i> —Ranges from approximately 20 to approximately 30.	5	<i>Reticulation.</i> —Absent.
<i>Average length.</i> —Approximately 7 mm.		<i>Roughness.</i> —Absent.
<i>Filament color.</i> —About white 155D.		<i>Tendency to crack.</i> —None.
<i>Anther color.</i> —About Grey-orange 167A.		Flesh:
<i>Flower pollen color.</i> —About Grey-orange 167A.	10	<i>Ripens.</i> —Evenly.
<i>Position.</i> —Perigynous.		<i>Texture.</i> —Firm, juicy.
Pistil:		<i>Fibers.</i> —Few.
<i>Number.</i> —Usually one, occasionally two.		<i>Flavor.</i> —Sweet-mild.
<i>Average length.</i> —Approximately 10 mm.		<i>Brix.</i> —Approximately 16°.
<i>Ovary diameter.</i> —Approximately 0.9 mm.		<i>Juice.</i> —Abundant to moderate.
<i>Pubescence.</i> —None.	15	<i>Aroma.</i> —Noticeable when ripe.
<i>Stigma extension in comparison to anthers.</i> —Usually below.		<i>Color.</i> —About 61C.
<i>Style pubescence (of base).</i> —Absent.		<i>Acidity.</i> —Medium-low.
Receptacle:		<i>Eating quality.</i> —Good.
<i>Depth.</i> —Medium.	20	<i>Stone/flesh ratio.</i> —1.9/34.
<i>Pubescence of inner surface.</i> —Absent.		<i>Firmness.</i> —Medium.
<i>Pubescence of outer surface.</i> —Absent.		Pit cavity size:
FRUIT		<i>Length (diameter in line with suture plane).</i> —Approximately 16 mm.
General: (Description taken near Wasco, Kern County, Calif.)		<i>Diameter perpendicular to suture plane.</i> —Approximately 12 mm.
<i>Harvest.</i> —	25	<i>Color.</i> —About 63C.
<i>Date of first pick.</i> —Approximately July 1.		Fruit use: Fresh market.
<i>Date of last pick.</i> —Approximately July 15.		Fruit shipping and keeping quality: Good, holds well in cold storage and maintains good firmness and eating quality, minimal bruising and scarring in packing and shipping trials.
Maturity when described: Firm.	30	Suture line: Inconspicuous.
Season ripening: Mid-season.		Stone: (Measurements taken on dried stones.)
Position of maximum diameter: Towards the middle.		<i>Stone freeness.</i> —Semi-free.
Symmetry about the suture: Nearly symmetric.		<i>Degree of adherence to flesh.</i> —Weak.
Size:		<i>Stone size.</i> —Size compared to Fruit: Small. Length (Diameter in line with suture plane): Approximately 16 mm. Diameter perpendicular to suture plane: Approximately 12 mm. Width of Stalk End: Medium; approximately 7 mm. Angle of Stalk end: Obtuse. Hilum: Broad.
<i>Length (stem end to apex).</i> —Approximately 66 mm.	35	<i>Stone form.</i> —Viewed from side: Somewhat oval, asymmetric. Viewed from ventral side: Somewhat oval. Viewed from stem end: Somewhat oval.
<i>Diameter perpendicular to suture plane.</i> —Approximately 66 mm.		<i>Stone shape.</i> —Base shape: Nearly straight. Apex shape: Nearly rounded to slightly pointed.
<i>Average weight.</i> —Approximately 150 gm.		<i>Stone surface.</i> —Furrowed and pitted throughout.
Form:	40	<i>Stone halves.</i> —Nearly symmetric.
<i>Viewed from apex.</i> —Rounded, nearly symmetrical.		<i>Stone ridges.</i> —Rounded irregularly throughout.
<i>Viewed from side, facing suture.</i> —Rounded, nearly symmetrical.		<i>Stone outgrowing keel.</i> —Partially developed.
<i>Viewed from side, perpendicular to suture.</i> —Rounded, nearly symmetrical.		<i>Stone tendency to split.</i> —Slight in wet season.
Apex shape: Rounded.	45	<i>Stone color.</i> —About 165C.
Fruit stem cavity:		<i>Position of maximum.</i> —Toward middle.
<i>Shape.</i> —Flaring, rounded.		<i>Ventral edge.</i> —Medium thin with slight wing.
<i>Depth.</i> —Approximately 0.5 cm.		<i>Dorsal edge.</i> —Medium shallow grooves interrupted.
<i>Breadth.</i> —Approximately 1 cm.		
<i>Width.</i> —Medium, approximately 15 mm.	50	What is claimed is:
Fruit stem:		1. A new and distinct plum tree as herein described and illustrated.
<i>Length.</i> —Approximately 9 mm.		
<i>Diameter.</i> —Approximately 3 mm.		
<i>Color.</i> —About 147D.		
Fruit skin:	55	
<i>Thickness.</i> —Medium, approximately 0.3 mm.		
<i>Adherence to flesh.</i> —Medium.		
<i>Surface texture.</i> —Smooth.		
<i>Pubescence.</i> —None.		
<i>Bloom.</i> —Medium, slight bloom.	60
